Filed Oct. 29, 1963, Ser. No. 77,203

Term of patent 14 years

(Cl. D66—1)

FIG. 3

FIG. 4

FIG. 1 is a perspective view of a railway tank car showing my new design;

FIG. 2 is an end view looking at the left hand end of FIG. 1;

FIG. 3 is a plan view of my new design; and

FIG. 4 is an elevational view showing the side of the car opposite the side shown in FIG. 1.

The dominant features of my design reside in the portions shown in full lines.

I claim:

The ornamental design for a railway tank car, substantially as shown and described.
